A. C. DOBRICK.
VALVE REGULATING MEANS.
APPLICATION FILED MAY 28, 1919.

1,339,811.

Patented May 11, 1920.

Inventor:

August C. Dobrick

August 1, 1892,
by John Howard McElroy,
his Atty.

UNITED STATES PATENT OFFICE.

AUGUST C. DOBRICK, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

VALVE-REGULATING MEANS.

1,339,811.

Specification of Letters Patent. Patented May 11, 1920.

Application filed May 28, 1919. Serial No. 300,372.

To all whom it may concern:

Be it known that I, AUGUST C. DOBRICK, a citizen of the United States, and a resident of Chicago, in the county of Cook and State 5 of Illinois, have invented certain new and useful Improvements in Valve-Regulating Means, of which the following is a full, clear, and exact specification.

My invention is concerned with valve 10 regulating means, and is concerned more especially with such a means adapted to be applied to the dashboard of an automobile for adjusting the position of the throttle valve of the intake of the engine carburetor 15 to control the air supply thereof.

To illustrate my invention, I have annexed hereto a sheet of drawings in which the same reference characters are used to designate identical parts in all the figures 20 of which—

Figure 1 is a side elevation of my invention shown as applied to the dashboard of an automobile;

Fig. 2 is a central longitudinal section of 25 the same on a larger scale; and

Figs. 3 and 4 are transverse sections on the lines 3—3 and 4—4, respectively, of Fig. 2.

In carrying out my invention, I prefer- 30 ably employ an externally threaded guide cylinder 10, in which is mounted to slide an adjusting rod 11, which will preferably be provided with a finger piece 12 secured thereto.

The cylinder is passed through a suitable 35 aperture in the dashboard 13 of an automobile, and is secured in place by the cap 14 screwed onto one end of the cylinder and resting against the front of the dashboard 40 13, while the set nut 15 and lock nut 15^a on the other side of the dashboard are screwed up, as shown in Fig. 1, to secure the parts securely in place. The adjusting rod 11 has secured to the inner end thereof the wire 45 16, which extends to and is secured to the throttle valve of the carburetor in the customary manner, it being guided and protected by the tube 17 preferably formed of spirally wound wire. This tube is secured 50 in place by the nut 18 through which it passes and which is threaded on the other end of the cylinder 10 from the outer end on which the cap 14 is screwed. The end of a wire 16 is conveniently looped through

the aperture 19 formed in the reduced end 55 of the adjusting rod 11.

To secure yieldingly the adjusting rod 11 in any desired position in the cylinder 10, I form on the rod a number of shallow annular grooves 20 corresponding to the number 60 of positions to which it is desired to adjust the valve, and coöperating with said grooves is a small helically coiled spring 21, consisting of two or more spires, and suitably confined in an annular recess 22 formed in 65 the cap 14 at the end thereof so that the spring 21 is confined between the end of the cylinder 10 and the bottom of the groove 22 in such a manner that the spring can not move except to expand sufficiently to allow 70 the rod 11 to pass from one position of adjustment to the other, the spring contracting after it passes each ridge between the adjacent grooves 20 so as to yieldingly hold the rod in any position of adjustment in a 75 manner that will be readily apparent.

Another feature of my invention is the novel combination by which the flexible tube 17 is secured to the cylinder 10, and to this end I taper off its end 23, and in said ta- 80 pered end I cut two or more slides 24, and form in the outer end of the nut 18 a cor- respondingly tapered portion 25. As the external diameter of the tube 11 is substan- 85 tially equal to the internal diameter of the cylinder 10, it will be obvious that when the parts are assembled, as seen at the left- hand end of Fig. 2, and the nut 18 is tightened up, the reduced end of the cylin- 90 der 10 will be contracted and will grip the tube 17 very tightly, and hold it as firmly as if it were soldered, while leaving it in condition so that it can be readily disconnected if the wire 16 is broken or it is de- 95 sired to put the outfit on another machine.

While I have herein shown and described my invention as embodied in the form which I at present consider best adapted to carry out its purposes, it is capable of some modification, and I do not desire to be 100 limited in the interpretation of the following claims, except as may be necessitated by the state of the prior art.

What I claim as new and desire to secure by Letters Patent of the United States is: 105

1. In an apparatus of the class described, the combination with a guide cylinder adapted to be secured in the dashboard of

an automobile, of an adjusting rod sliding therein and provided with annular grooves thereon, a short coiled spring surrounding said rod and adapted to coöperate singly with any of said grooves, and means for confining the spring to prevent its movement with the rod while permitting expansion to allow the rod to be adjusted to and held in any of its positions of adjustment.

10 2. In an apparatus of the class described, the combination with a guide cylinder adapted to be secured in the dashboard of an automobile, of an adjusting rod sliding therein and provided with annular grooves thereon, a short coiled spring surrounding said rod and adapted to coöperate singly with any of said grooves, and a cap screwed on one end of the cylinder and having an annular recess therein adjacent said end of the proper dimensions to receive and confine the spring in the manner and for the purpose set forth.

15 3. In an apparatus of the class described, the combination with an externally threaded 20 guide cylinder, of an adjusting rod sliding therein and provided with annular grooves thereon, a short coiled spring surrounding said rod and adapted to coöperate singly

with any of said grooves, a cap adapted to be screwed on one end of the cylinder and 30 having an annular recess therein of the proper dimensions to receive and confine the spring therein for the purpose described, and a nut screwed on the cylinder for the purpose described.

35 4. In an apparatus of the class described, the combination with a guide cylinder adapted to be secured in the dashboard of an automobile and having its rear end externally threaded and provided with a tapered, split portion, of an adjusting rod sliding therein, means for holding the rod in any desired position of adjustment, a wire attached to the end of the rod, a flexible tube adapted to fit in the end of 40 the cylinder, and a nut threaded on the rear end of the cylinder and having a reduced internally tapered portion coöperating with the tapered and split end of the cylinder for the purpose described.

45 In witness whereof I have hereunto set my hand and affixed my seal this 20th day of May, A. D. 1919.

AUGUST C. DOBRICK. [L.S.]
Witness:
JOHN HOWARD McELROY.
